UNITED STATES PATENT OFFICE.

JOSEPH B. McCUNE, OF HARTFORD, CONNECTICUT, ASSIGNOR TO ELIAS A. WILKINSON, OF NEWARK, NEW JERSEY.

FEEDING MECHANISM FOR SEWING-MACHINES.

SPECIFICATION forming part of Letters Patent No. 268,704, dated December 5, 1882.

Application filed June 20, 1882. (No model.)

To all whom it may concern:

Be it known that I, JOSEPH B. McCUNE, of Hartford, in the county of Hartford and State of Connecticut, have invented certain new and useful Improvements in Feeding Mechanism for Sewing-Machines, described in this specification and the drawings thereof.

The invention consists of improvements relating to the cam and yoke of the feed mechanism to provide for adjustment and compensate for wear.

Figure 1 is a front view of a portion of a sewing-machine embracing the improvements. Fig. 2 is a side view of the improvements detached from the machine. Fig. 3 is a front view of the same. Fig. 4 is a detail view of portions thereof.

In the form of construction shown the driving shaft A has a double cam, B, having lobes O P on opposite sides of the driving-shaft to give vertical and lateral motion to the vertical feed-lever C by contact at upper and lower and side points of the yoke D, which is preferably made oblique, and is cut away at the opposite parts, Q R and S T, leaving the bearings U V for the lobe O of the cam to raise and lower the vertical lever, and the bearings W X for the lobe P of the cam to vibrate the vertical lever. For adjustment in assembling the parts and for compensating for the wear of the cam and yoke, wedges E F are placed between the yoke and the cam, and made adjustable by slots and set-screws G H in the yoke. The wedge F and the yoke may be so construct-

ed as to have the set-screw in the point K of 35 the wedge, so that both wedges can be easily adjusted through the opening L in the arm M of the machine.

The details of construction may be varied within the scope of my improvements. 40

I claim as my invention—

1. The combination, in sewing mechanism, of a driving-shaft, A, a cam, B, thereon, having lobes O P, arranged on opposite sides of the driving-shaft, an oblique yoke, D, having bearings U V W X, adjustable wedges E F, and lever C, substantially as set forth. 45

2. The combination, in sewing mechanism, of a driving-shaft, having a double cam, with lobes on opposite sides of the shaft, and a feed-lever having an oblique yoke with opposite offset bearings for each lobe, the bearings being provided with adjustable wedges, substantially as set forth. 50

3. The combination, in sewing mechanism, of a driving-shaft, a yoke having opposite adjustable offset bearings, and a cam having lobes on opposite sides of the driving-shaft to operate against the bearings, substantially as set forth. 55

In testimony whereof I hereunto subscribe my signature, in the presence of two attesting witnesses, on the 31st day of May, 1882.

JOSEPH B. McCUNE.
